UNITED STATES PATENT OFFICE.

ANTONIO PENTIFALLO, OF HOLLIDAYSBURG, PENNSYLVANIA.

LIFT FOR SHOE HEELS.

Original application filed August 21, 1923, Serial No. 658,559. Divided and this application filed September 11, 1924. Serial No. 737,138.

To all whom it may concern:

Be it known that I, ANTONIO PENTIFALLO, a citizen of the United States of America, residing at Hollidaysburg, in the county of Blair and State of Pennsylvania; have invented certain new and useful Improvements in Lifts for Shoe Heels, of which the following is a specification.

This invention relates to new and useful improvements in lifts for shoe heels and has particular reference to those constructed of resilient material. This application constitutes a division from my copending application Serial No. 658,559, filed August 21, 1923.

An important object of the invention is to provide various forms of shoe heel lifts which are constructed from resilient material and are adapted for more accurately fitting the heel base of a shoe.

Other objects and advantages of the invention will be apparent during the course of the following description.

In the accompanying drawing forming a part of the specification and in which like numerals are employed to designate like parts throughout the same,

Figure 1 is a top plan view of an improved form of shoe heel lift embodying this invention,

Figure 2 is an end elevational view of the lift shown in Fig. 1,

Figure 3 is a top plan view of a modified form of heel lift, and

Figure 4 is a transverse sectional view taken upon line IV—IV of Fig. 3.

Referring to the accompanying drawing and particularly to Figs. 1 and 2, the numeral 5 designates a heel lift, in its entirety, formed from a suitable resilient material and having a wedge-shaped depression 6 formed therein that is positioned with its wider end at the front edge 7 of the lift and with its pointed end terminating at the rear side 8 of the lift. The longitudinal side edges of this wedge-shaped depression 6 are provided with inclined, upwardly extending walls 9 that merge into the top surfaces 10.

In Figs. 3 and 4, the heel lift 5^a is pro-

vided with a wedge-shaped depression 11 which is positioned with its wider end at the rear side 12 of the heel lift while the point or apex of the depression 11 terminates at the front edge 13 of the lift. The forwardly converging side walls 14 of this wedge-shaped depression 11 are formed truly perpendicular in respect to the bottom wall of the depression 11 and form, at their outer longitudinal edges, the inner edges of the bulging surfaces 15.

It will be seen by inspecting Figs. 2 and 4, that these heel lifts 5 and 5^a are of substantially convexo-concave formation. It is to be understood that the lifts are to be applied to the under surfaces of shoe heels with the surfaces 10 and 15 touching the heels. Suitable fastening means, such as nails or the like, are to be driven through the portions of the lifts not having the wedge-shaped depressions formed therein and the lifts are to be drawn tightly against the heel face for causing the former to change from their convexo-concave formations into flat lifts.

It is to be understood that the forms of this invention herewith shown and described are to be taken as the preferred examples of the same, and that various changes in the shape, size, and arrangement of parts may be resorted to without departing from the spirit of the invention or the scope of the subjoined claim.

Having thus described the invention, I claim:

In a lift for shoe heels comprising a piece of resilient material of substantially convexo-concave formation, a depression formed in the upper surface of said lift, raised sections formed laterally of said depression, opposing upwardly directed and longitudinally converging walls connecting the surface of said raised sections and the surface of said depression, said raised sections having their upper surfaces transversely convexed throughout their length, and means for securing said lift upon a shoe heel.

In testimony whereof I affix my signature.

ANTONIO PENTIFALLO.
